UNITED STATES PATENT OFFICE.

JOHN W. SLAYTON, OF SALEM, OHIO, ASSIGNOR OF ONE-HALF TO CHARLES GORE, OF SAME PLACE.

DESIGN FOR A SCISSORS-SHARPENER FRAME OR BLOCK.

SPECIFICATION forming part of Design No. 25,126, dated February 4, 1896.

Application filed May 10, 1895. Serial No. 543,869. Term of patent 7 years.

To all whom it may concern:

Be it known that I, JOHN W. SLAYTON, a citizen of the United States, residing at Salem, in the county of Columbiana and State of Ohio, have invented a new and original Design 5 for a Scissors-Sharpener Frame or Block, of which the following is a specification.

This invention relates to a new and original design for a scissors-sharpener frame or block; 10 and it has for its object to provide a design of this character that shall be both useful and ornamental.

The leading feature of the design resides in a rectangularly-shaped body provided intermediate of its upper and lower sides with a pair of longitudinal closely-arranged parallel lines forming separate upper and lower horizontal body portions, the upper of which horizontal body portion is shorter than the lower 15 horizontal body portion and is provided at its shortened end with a rectangularly-shaped figure extending diagonally from side to side of the body and disposed at an acute angle to the flat upper face thereof, said upper horizontal body portion having an undercut portion 20 directly adjacent to said rectangularly-shaped figure and disposed directly over the flat upper side of the lower horizontal body portion.

25 In the drawings, Figure 1 is a perspective

view of a scissors-sharpener frame or block embodying the herein-described design. Fig. 2 is a side elevation thereof.

Referring to the accompanying drawings, the numeral 1 designates a rectangularly-shaped body provided intermediate of its upper and lower sides with a pair of longitudinal closely-arranged parallel lines 2, forming separate upper and lower horizontal body portions 3 and 4 respectively. The upper horizontal body portion 3 is shorter than the portion 4 and is provided at its shortened end with a rectangularly-shaped figure 5, extending diagonally from side to side of the body and disposed at an acute angle to the flat upper face thereof. The upper portion 3 is further provided directly adjacent to the rectangular figure 5 with an undercut portion 6, disposed directly over the flat upper side of the lower portion 4 of the body. 35 40 45 50

What I claim is—

The design for a scissors-sharpener frame or block herein shown and described.

In testimony that I claim the foregoing as my own I have hereto affixed my signature in 55 the presence of two witnesses.

JOHN W. SLAYTON.
